Harry F. Roach.
By Bakewell & Church attys.

UNITED STATES PATENT OFFICE.

HARRY F. ROACH, OF ST. LOUIS, MISSOURI.

RAIL-JOINT.

1,320,572.

Specification of Letters Patent.

Patented Nov. 4, 1919.

Application filed January 6, 1919. Serial No. 269,819.

To all whom it may concern:

Be it known that I, HARRY F. ROACH, a citizen of the United States, residing at St. Louis, Missouri, have invented a certain new and useful Improvement in Rail-Joints, of which the following is a full, clear, and exact description, such as will enable others skilled in the art to which it appertains to make and use the same.

10 This invention relates to a rail joint of the particular type described in my prior U. S. Patent No. 1,258,252, dated March 5, 1918, namely, a rail joint in which the rails move vertically at the ends of the joint, both upwardly and downwardly under load, and fulcrum on the side members of the joint at separated points in proximity to the center bolts of the joint.

15 The main object of my present invention is to provide a rail joint, which, in addition to possessing all of the good points and characteristics of the rail joint described in my prior patent previously referred to, has the following desirable features which make 20 it an improvement on my said prior joint; it can be rolled; it has rail engaging surfaces which can be formed from material that has great wear resisting properties and it is provided with inexpensive renewable 25 parts that receive practically all of the wear 30 to which the joint is subjected when the joint is in service.

Briefly described, my improved joint consists of two side members, each of which is 35 composed of a renewable fulcrum member that is arranged in engagement with the rails at the center of the joint, and a longitudinally-disposed bar that holds said renewable fulcrum member in engagement 40 with the rails in such a manner that it provides fulcrum points on which the under sides of the heads and the upper sides of the base flanges of the rails bear at points a slight distance at either side of the exact 45 center of the joint, said bar being so formed that it will not interfere with the vertical movement of the rails at the ends of the joint, both upwardly and downwardly, when the rails fulcrum on said fulcrum member 50 under load. Said bar is preferably of constant cross section, thereby enabling it to be rolled easily, and it can be formed of comparatively soft metal, in view of the fact that it is subjected to relatively little wear 55 or abrasion when the joint is in service. The

renewable fulcrum member can either be rolled, forged or pressed and it can be formed from material that has great wear resisting properties, such, for example, as high carbon steel, heat treated.

60 Figure 1 of the drawings is a side elevational view of a rail joint constructed in accordance with my present invention.

Fig. 2 is a top plan view of said rail joint, partly in horizontal section.

65 Fig. 3 is an end elevational view of the joint, showing one of the side members in vertical cross section.

Fig. 4 is a perspective view of one of the renewable fulcrum members; and

70 Figs. 5 and 6 are side elevational views, illustrating renewable fulcrum members of slightly different form.

75 Referring to the drawings, which illustrate the preferred form of my invention, A designates two abutting rails which are embraced by the two side members of the joint, each of which side members is composed of a bar B that extends longitudinally of the rails and a renewable fulcrum member C arranged at the center of the joint and combined with said bar in such a manner that it will be held in engagement with the under sides of the heads of the rails and the upper sides of the base flanges of the rails.

85

80 The renewable fulcrum member C preferably conforms approximately to the fishing section of the rails and is provided with two rail engaging portions 1 and 2 that are disposed at substantially the same angles as the 90 under sides of the heads of the rails and the upper sides of the base flanges of the rails. Said rail engaging portions 1 and 2 are connected together by a vertical web 3 that is provided with notches 4, as shown in Fig. 4, 95 or holes 4*, as shown in Figs. 5 and 6, for receiving the center bolts 5 of the joints. The web 3 can be of the same or less thickness as the rail engaging portions 1 and 2, as the only function that said web performs is to 100 hold the rail engaging portions 1 and 2 in proper spaced relation and prevent said member C from moving longitudinally in either direction. The bar B is so shaped that when it is first arranged in engagement 105 with the renewable member C, the rail engaging portions 1 and 2 of said member will hold the bar in such a position with relation to the rails that the end portions of said bar will be spaced away from the webs of the 110

rails before the end bolts 6 of the joint are tightened.

To install the joint the renewable fulcrum members C are first arranged at the opposite sides of the rails at the center of the joint and the bars B are then inserted between the rail engaging portions 1 and 2 of the renewable member C. The center bolts 5 are then tightened so as to draw the bars B into snug engagement with the rail engaging portions 1 and 2 of the parts C, and thereafter the end bolts 6 of the joint are tightened so as to draw the end portions of the bars B inwardly into engagement with the webs 10 of the rails, as shown in Fig. 2. The center portions of the bars B are prevented from moving inwardly toward the rails by the engagement of the upper and lower edges 15 of said bars with the rail engaging portions 20 1 and 2 on the renewable fulcrum members C. Consequently, when the end bolts 6 of the joint are tightened, the bars B will bow out slightly at the center of the joint, as shown in Fig. 2, thereby causing said bars 25 to exert pressure on the rail engaging portions 1 and 2 of the members C at the ends of said members, and consequently, producing a slight relief between the bars B and the rail engaging portions 1 and 2 at the 30 center of the joint. In other words, the operation of tightening the end bolts 6 causes the bars B to force the ends of the rail engaging portions 1 and 2 into snug engagement with the heads and base flanges 35 of the rails, thereby causing the rails to fulcrum on the ends of the rail engaging surfaces 1 and 2 of the renewable fulcrum member C in substantially the same manner that the rails fulcrum on the rail engaging 40 surfaces of the side members of the joint described in my prior patent previously referred to. The upper and lower edges of the bars B of course bear against the rail engaging portions 1 and 2 throughout the 45 entire length of said rail engaging portions, but the actual fulcrum points of the rails on the portions 1 and 2 are at the ends of said portions, due to the fact that when the ends of the bars B are drawn inwardly 50 sufficiently to bow out the center portions of said bars, a slight relief will be provided between said bars and the intermediate portions of the rail engaging surfaces 1 and 2 on which the extreme ends or terminals of 55 the rails bear. While I have herein shown the rail engaging portions 1 and 2 of the joint constructed in such a manner that they contact with the heads and base flanges of the rails throughout the entire length of 60 said portions, it will, of course, be obvious that the rail engaging portions 1 and 2 could be so constructed that they would not bear against the terminals or extreme ends of the rails. I prefer to construct the renewable 65 fulcrum members C in the manner herein

illustrated, however, because such a design simplifies the operation of manufacturing the joint and it is as efficient as a design in which the rail engaging portions 1 and 2 are of such shape that they do not contact 70 directly with the terminals of the rails.

A rail joint of the construction above described permits the wave motion of the rails throughout the track to be continued uniformly through the joints of the track; it 75 provides a slight relief for the terminals or extreme ends of the rails at the center of the joint, thereby reducing the stiffness of the portions of the rails that are embraced by the side members of the joint; it can be manufactured at a low cost, owing to the fact that the bars B can be rolled and the renewable fulcrum members C can either be rolled, forged or pressed; it is of such design that the rail engaging surfaces of same 80 can be formed of high carbon steel or other metal that has great wear resisting properties and it can be maintained in a highly efficient condition, with minimum trouble and expense, owing to the fact that the only 85 portions of same which are subjected to severe wear are the renewable fulcrum members C. When the joint is in service there is practically no slippage between the bars B and the fulcrum members C. Consequently, 90 the bars B can be used indefinitely, as they are subjected to little or no wear when the joint is in service.

In instances where the center bolts of the joint are spaced relatively far apart, the web 1 of the renewable fulcrum member C is provided with lateral extensions, as shown in Fig. 5, equipped with holes 4^a through which the center bolts pass.

I prefer to form the renewable fulcrum member C in one piece, as shown in Figs. 4 and 5, but, if desired, the renewable fulcrum member can be composed of two horizontally-divided sections 7, as shown in Fig. 6.

Having thus described my invention, what I claim and desire to secure by Letters Patent, is:

1. A rail joint provided with side members that are arranged on opposite sides of the rails, each of said side members being composed of a renewable fulcrum member having portions that bear against the heads and base flanges of the rails, and a bar or member that holds said fulcrum member in engagement with the rails in such a manner that a slight relief is provided at the center of the joint for the extreme ends or terminals of the rails.

2. A rail joint provided with side members that are arranged on opposite sides of the rails, each of said side members being composed of a renewable fulcrum member having portions that bear against the heads and base flanges of the rails, and a bar or mem-

- ber that holds said part in engagement with the rails in such a manner that the rails will fulcrum on said fulcrum member at points in proximity to the center bolts of the joint.
5. 3. A rail joint, comprising side members arranged on opposite sides of the rails, each of said side members being composed of a renewable fulcrum member having rail engaging portions that bear against the undersides of the heads and the upper sides of the base flanges of the rails, and a bar or member combined with said renewable fulcrum member in such a manner that when the end bolts of the joint are tightened the 10 ends of said rail engaging portions will be forced into sufficiently snug engagement with the rails to form fulcrum points for the rails located at either side of the center of the joint.
15. 4. A rail joint, comprising side members arranged on opposite sides of the rails and each composed of a renewable fulcrum member having rail engaging portions whose ends bear against the heads and the base flanges of the rails and form fulcrum points for the rails at points in proximity to the center bolts of the joint, and a bar or member for holding said renewable fulcrum member in position, constructed in such a 20 manner that it does not interfere with the vertical movement of the rails upwardly and downwardly when the rails fulcrum on said fulcrum member under load.
25. 5. A rail joint, comprising side members arranged on opposite sides of the rails and each composed of a renewable fulcrum member having rail engaging portions which bear against the under sides of the heads and the top sides of the base flanges of the 30 rails, and a bowed bar or member for holding said renewable fulcrum member in position, the end portions of said bar being spaced away from the heads and base flanges of the rails, for the purpose described.
35. 6. A rail joint member, comprising a fulcrum member provided with rail engaging portions that bear against the heads and the base flanges of the rails, and a longitudinally-disposed bar or member combined 35 with said fulcrum member in such a manner that when the end bolts of the joint are tightened the intermediate portion of said bar will be bowed out at the center of the joint, thereby causing the bar to force the ends of said rail engaging portions into sufficiently snug engagement with the heads and base flanges of the rails to form fulcrum points for the rails located far enough away from the center of the joint to provide a slight relief for the terminals of the rails.
45. 7. A rail joint member composed of a fulcrum member adapted to be arranged at the center of the joint and provided with rail engaging portions that coöperate with the heads and base flanges of the rails, and a 50
- longitudinally-disposed bar or member interposed between said rail engaging portions and so designed that it will be spaced far enough away from the webs of the rails to cause the center portion of said bar to 70 bow out when the end bolts of the joint are tightened, thereby causing the rail engaging portions on said fulcrum member to bear against the rail in such a manner that a slight relief is provided for the terminals 75 of the rails when the joint is in service.
8. A rail joint member, comprising a renewable fulcrum member that conforms approximately to the fishing section of the rails and which is adapted to be arranged 80 at the center of the joint between the heads and base flanges of the rails, and a bar or member adapted to be arranged longitudinally of the rails with its intermediate portion bowed outwardly and its upper and 85 lower edges bearing against portions on said renewable fulcrum member that co-operate with the heads and base flanges of the rails to form fulcrums for the rails, said bar being so designed that it will not 90 contact with the heads and base flanges of the rails at the ends of the joint when the rails fulcrum on said fulcrum member.
9. A renewable fulcrum member for rail joints, consisting of a member adapted to be 95 arranged at the center of the joint at one side of the rails and provided at its upper edge with a rail engaging portion of less length than the distance between the end bolts of the joint that coöperates with the 100 heads of the rails.
10. A renewable fulcrum member for rail joints of the type referred to, consisting of a member of less length than the joint adapted to be arranged in engagement with 105 the under sides of the heads of the rails in proximity to the center bolts of the joint.
11. A renewable fulcrum member for rail joints, of the type referred to, consisting of a member of less length than the distance between the end bolts of the joint and provided at its upper side with a rail engaging portion that forms fulcrum points for the rails located adjacent the center 110 bolts of the joint.
12. A renewable fulcrum member for rail joints, of the type referred to, consisting of a member of less length than the joint, adapted to be arranged at the center of the joint at one side of the rails and provided 115 with rail engaging portions that coöperate with the heads and base flanges of the rails to form fulcrum points for the rails located in proximity to the center bolts of the joint.
13. A renewable fulcrum member for rail 120 joints of the type referred to, consisting of a member of substantially channel shape in vertical cross section that is adapted to be arranged at the center of the joint at one side of the rails, the flanges at the upper 125
- 130

- 4
- and lower edges of said member constituting rail engaging portions whose ends terminate in proximity to the center bolts of the joint.
- 5 14. A renewable fulcrum member for rail joints of the type referred to, consisting of a member provided with a vertically-disposed web that extends parallel to the webs of the rails of the joint, and rail engaging portions on said web that coöperate with the heads and base flanges of the rails, said rail engaging portions being of less length than the distance between the end bolts of the joint.
15. A renewable fulcrum member for rail joints of the type referred to, consisting of a horizontally-divided member adapted to be arranged at the center of the joint at one side of the rails and provided with rail engaging portions of less length than the distance between the end bolts of the joint that coöperate with the heads and base flanges of the rails.

HARRY F. ROACH.

It is hereby certified that in Letters Patent No. 1,320,572, granted November 4, 1919, upon the application of Harry F. Roach, of St. Louis, Missouri, for an improvement in "Rail-Joints," errors appear in the printed specification requiring correction as follows: Page 2, line 8, for the word "member" read *members*; page 3, line 74, claim 7, for the word "rail" read *rails*; and that the said Letters Patent should be read with these corrections therein that the same may conform to the record of the case in the Patent Office.

Signed and sealed this 25th day of November, A. D., 1919.

[SEAL.]

M. H. COULSTON,
Acting Commissioner of Patents.
